UNITED STATES PATENT OFFICE.

CARL R. DAELLENBACH, OF BRADDOCK, PENNSYLVANIA, ASSIGNOR OF ONE-HALF TO
J. WENDELL VERNAM, OF SWISSVALE, PENNSYLVANIA.

INTERNAL-COMBUSTION ENGINE.

No. 909,558.

Specification of Letters Patent. Patented Jan. 12, 1909.

Application filed January 24, 1908. Serial No. 412,450.

To all whom it may concern:

Be it known that I, CARL R. DAELLENBACH, citizen of the United States, residing at Braddock, in the county of Allegheny and State of Pennsylvania, have invented new and useful Improvements in Internal-Combustion Engines, of which the following is a specification.

My invention pertains to internal combustion engines of the two-cycle type; and it has for its object to provide an internal combustion engine of such type which without being unduly expensive is safe and reliable in operation and is adapted to use gas and gasoline as fuel.

The novelty, utility and practical advantages of the invention will be fully understood from the following description and claims when the same are read in connection with the drawings, accompanying and forming part of this specification, in which:

Figure 1 is a view partly in elevation and partly in section illustrating a two-cycle internal combustion engine constituting the best practical embodiment of my invention of which I am cognizant. Fig. 2 is a transverse section taken through the outer portion of the explosion chamber and the parts adjacent thereto, and: Fig. 3 is a detail section taken at a right angle to Fig. 1 and illustrating the automatic, fuel-valve operating mechanism which I prefer to employ.

Similar letters designate corresponding parts in all of the views of the drawings, referring to which:

A is the cylinder of my novel engine which is divided by a reciprocating piston B into an explosion chamber C and a crank case D. The explosion chamber C is provided at the point shown with an exhaust port a, and the crank case D has an inlet b for air, and intermediate the chamber C and the case D a conduit E is provided, which conduit E extends upward from the induction port c of the chamber C and then downward to the point where it is connected with the eduction port d of the crank case. By virtue of this arrangement of the conduit E it will be manifest that the gas or gasoline employed as fuel is effectually prevented from reaching the crank case and injuriously affecting the lubricated parts of the engine.

As shown in Fig. 1, the shaft F of the engine is provided within the case D with a crank wheel G, and intermediate the piston

B and the said crank wheel or disk G is a pitman H for transmitting motion from the former to the latter. The perimeter of the crank wheel or disk G is flanged as indicated by e, and the side of the said flange remote from the pitman H is concaved, as indicated by f, and arranged as shown relative to the eduction port of the crank case D, whereby it will be seen that the said crank wheel or disk is adapted to guard the said eduction port and prevent lubricating oil from being thrown into the same, and this without preventing the passage of fluid under pressure from the crank case to the said eduction port.

Extending into the conduit E from one side thereof and at a point adjacent to the induction port c of the explosion chamber C is a tube I, Fig. 2, which is designed to be connected with a source of gasoline supply and is equipped with a suitable non-return valve J. The inner portion of the bore of said tube I is tapered as indicated by g to receive the tapered end h of a needle valve K, which needle valve is provided at i with an enlargement or abutment and is extended loosely through a tubular valve L for controlling the introduction of gas. The gas is supplied to a conduit M, which conduit is provided at N with a non-return valve and is connected with the conduit E through a taper port j designed to seat the inner tapered end of the tubular valve L. The portion of the needle valve K which extends beyond the outer end of the tubular valve L is threaded as indicated by k and is equipped with one or more, preferably two, nuts l between which and the outer end of the tubular valve L is arranged a collar m which is loosely mounted on the needle valve and is circumferentially grooved for a purpose presently set forth. A coiled spring P is mounted on the needle valve K between the abutment i thereof and the inner end of the tubular valve L, and hence it will be manifest that when the collar m is moved outwardly, the valve K will first be opened to admit gasoline or the like to the conduit E, and then the valve L will be opened to supply gas to the conduit E. It will also be manifest that on movement of the collar m in the direction opposite to that indicated by arrow the needle valve K will be seated prior to the seating of the tubular valve L.

The practical operation of my novel en-

gine is as follows: In Fig. 1, the piston B is shown at the outer extremity of its stroke, and incidental to the subsequent inward movement of the piston it serves to compress explosive mixture in the explosion chamber C, and also serves to create a partial vacuum in the crank chamber or case D. The fuel valves K and L being at that time open, the said partial vacuum will cause a certain quantity of fuel to enter the conduit E at a point adjacent to the induction port c, this being advantageous because the fuel will offer but little resistance to the air while the latter is on its way to the explosion chamber C; and also because the gas will enter the explosion chamber ahead of the air and being a non-explosive mixture will sweep out the products of combustion of the previous explosion. On the subsequent outward movement of the piston B, the air is compressed in the crank case D, and then when said piston uncovers the port c, the fuel and the gas will enter the explosion chamber in the manner and for the purpose just set forth, after which on the inward stroke of the piston B the explosive mixture is compressed by the piston B until it is ignited by compression or by a suitable igniting device (not illustrated), whereupon the piston will be forced outward and the operation described in detail will be repeated.

It will be gathered from the foregoing that the efficiency of my novel engine is due to the throttling of the fuel alone, the sweeping of the cylinder with gas incidental to each revolution, the separation of the fuel and air until the same are supplied to the explosion chamber, and the adaptability of the engine to use liquid and gaseous fuel. It will also be appreciated that heavy oil or liquid fuel may be used because it is introduced through the hot metal of the engine and is swept into the cylinder by hot air, and that the explosive mixture does not enter the crank case where it would be likely to interfere with lubrication of the working parts and to cause back explosions. It will further be noted that in my novel engine air is removed from the crank case without sub- jecting the lubricating oil to suction, that gasolene or liquid fuel may be piped direct into the engine which increases the element of safety inasmuch as in the event of fire there is no liquid fuel exposed in the apartment where the engine is located, that liquid fuel is drawn into the engine on inward or upward movement of the piston which renders it feasible to keep the fuel at a lower level than that of the tube I, so that when the engine stops the liquid fuel will not flood the engine.

A rock-shaft R having an arm S in engagement with the collar m is provided, and through the medium of the said rock-shaft the valves K and L may be operated by hand

or by any other suitable means when it is not desired to automatically govern the speed of the engine. When the valves K and L are operated—i. e., opened and closed, by hand, the operator grasps the arm Y, 70 presently described, on the rock-shaft R and swings said arm to and fro. I prefer, however, to actuate the rock-shaft R through the medium of the hit and miss mechanism shown in Figs. 1 and 3, which mechanism 75 comprises an eccentric T on the engine shaft F, a strap U surrounding said eccentric, a rod V fixed to the strap U and having an upper open portion W in which is disposed the tapered head X on the arm Y of the rock-shaft R, and a pick-blade Z pivoted to the rod V and arranged under normal conditions to engage the tapered head X and open the valves K and L incidental to each upward movement of the rod V, and also 80 arranged when the speed of the engine becomes greater than that predetermined, to assume the position shown by dotted lines in Fig. 1 so as to clear the taper head X until the speed of the engine is reduced to 85 normal. The pick-blade Z is preferably provided with a weighted arm Z' to assist its outward movement, and it is held under normal conditions in the position shown by full lines in Fig. 1 through the medium 90 of a coiled spring Z² which is mounted 95 upon a rod Z³ fixed to the rod V and extending loosely through the pick-blade Z, and is interposed between the said pick-blade Z and a nut Z⁴ mounted on the rod Z³. To adjust the speed of the engine the nut Z⁴ may be turned in or out to compress the spring Z² or permit expansion of the same as occasion demands, and the speed 100 may also be adjusted by adjusting the weight on the arm Z'. The eccentric T is fixed on the engine shaft F in such position as to assure opening of the fuel valves K and L on the inward stroke of the piston B, this in order to admit fuel during the said 105 stroke, and to permit closing of the said valves on the outward or downward stroke of the piston so as to prevent the pressure of air in the fuel supply pipes. It will be also noted that by reason of the nut or nuts 110 l on the needle valve K and the interposition of the spring P between the abutment i on said valve and the inner end of the tubular valve L, the valves may be adjusted as 115 occasion demands. 120

It will be understood from the foregoing that in the event of the supply of gasolene failing or being shut off for any reason, my improved engine will utilize gas alone as a fuel, and that in case of the supply of gas 125 failing or being shut off for any reason the engine will utilize gasolene alone as a fuel.

As before stated, the construction herein illustrated and described constitutes the best practical embodiment of my invention 130

known to me, but it is obvious that in the future practice of the invention various changes in the form, construction and relative arrangement of the parts may be made 5 without involving departure from the scope of my invention as defined in the claims appended.

Having described my invention, what I claim and desire to secure by Letters-Pat- 10 ent, is:

1. In an internal combustion engine, a cylinder divided by a piston into an explosion chamber and a crank case or chamber and having a conduit which is closed to the 15 explosion chamber except when the piston is at the extremity of its outward stroke and which extends laterally from said chamber and then in a direction away from the crank case or chamber and then extends toward 20 the crank case or chamber and communicates therewith, and also having means for supplying fuel to the portion of the conduit adjacent to the explosion chamber.

2. In an internal combustion engine, a cylinder divided by a piston into an explosion chamber and a crank case or chamber and having a conduit which communicates at one end with the explosion chamber and extends from such point of communication 30 longitudinally of the cylinder in a direction away from the crank case or chamber and then extends longitudinally of the cylinder toward the crank case or chamber and communicates therewith, and also having means 35 for supplying fuel to the portion of the conduit adjacent to the explosion chamber, in combination with a crank disk connected with the piston and arranged to prevent the passage of lubricant from the crank case or 40 chamber to the conduit without preventing the passage of air from the crank case or chamber to the conduit.

3. In an internal combustion engine, a cylinder divided by a piston into an explosion 45 chamber and a crank case or chamber and having a conduit which communicates at one end with the explosion chamber and extends from such point of communication longitudinally of the cylinder in a direction 50 away from the crank case or chamber and then extends longitudinally of the cylinder toward the crank case or chamber and communicates therewith, and also having means 55 for supplying liquid fuel to one side and means for supplying gas to the other side of the portion of the conduit adjacent to the explosion chamber.

4. In an internal combustion engine, a cylinder divided by a piston into an explosion 60 chamber and a crank case or chamber and having a conduit intermediate the said chambers and also having an inlet at one side of the conduit for gas and an inlet at the opposite side of the conduit for liquid

fuel, valves for controlling said inlets, and 65 means common to the said valves for opening and closing the same.

5. In an internal combustion engine, a cylinder divided by a piston into an explosion chamber and a crank case or chamber 70 and having a conduit intermediate the said chambers, and also having an inlet for liquid fuel in one side of the conduit and an inlet for gas in the other side of the conduit, in combination with a valve for controlling 75 the liquid-fuel inlet, and a valve for controlling the gas inlet; one of the said valves extending through the other and being connected therewith.

6. In an internal combustion engine, a cylinder divided by a piston into an explosion chamber and a crank case or chamber and having a conduit intermediate the said chambers, and also having an inlet for liquid fuel in one side of the conduit and an inlet 85 for gas in the other side of the conduit, in combination with a valve arranged to control the liquid-fuel inlet and extending through the gas inlet and having an abutment, a valve surrounding the first mentioned valve and arranged to control the gas inlet, a coiled spring surrounding the first mentioned valve and interposed between the abutment thereof and the other valve, adjustable means on the first mentioned valve, 90 and means for operating the valves arranged on the first mentioned valve between said adjustable means and the second mentioned valve.

7. In an internal combustion engine, a cylinder divided by a piston into an explosion chamber and a crank case or chamber and having a conduit intermediate the said chambers and also having an inlet for liquid fuel in one side of the conduit and an inlet 100 for gas in the other side of the conduit, in combination with a crank shaft connected with the piston, a valve arranged to control the liquid-fuel inlet and extending through the gas inlet and having an abutment, a valve surrounding the first mentioned valve and arranged to control the gas inlet, a coiled spring surrounding the first mentioned valve and interposed between the abutment thereof and the other valve, adjustable means on the first mentioned valve, 105 and speed-controlling means actuated by the crank shaft and arranged on the first mentioned valve between the said adjustable means and the second mentioned valve. 110

In testimony whereof I have hereunto set my hand in presence of two subscribing witnesses.
